UNITED STATES PATENT OFFICE.

FRITZ WITTE, OF BRUNSWICK, GERMANY.

TRANSPORTING DEVICE.

1,409,806.

Specification of Letters Patent. Patented Mar. 14, 1922.

Application filed August 13, 1919. Serial No. 317,342.

To all whom it may concern:

Be it known that I, FRITZ WITTE, residing at Brunswick, Germany, 5 Cyriaksring, have invented certain new and useful Improvements in a Transporting Device, (for which I have filed an application in Germany, Aug. 1, 1918,) of which the following is a specification.

My invention relates to transporting devices and more especially to overhead transporters of the twin rope type, where one truck passes on top of the other when they meet on the open track, the buckets being suspended from the trucks at different distances from the longitudinal axis of the track so that they too will travel past each other when the one truck is overriding the other.

As is well known, aerial railways or rope-ways of this system require two kinds of trucks of different construction, one for each direction, and the trucks of the one kind will of necessity accumulate at the head station until the line has been cleared in order to avoid collisions.

In the transporting device according to the present invention trucks of easily variable breadth are employed and it is therefore possible to change the breadth of the truck, after it has traveled over the track in one or the other direction, so that after being loaded or discharged it may be dispatched anew without any delay. In this manner the trucks are enabled to pass one on top of the other at a turn-out.

In the drawings affixed to this specification and forming part thereof the preferred form of a transporter according to the present invention is illustrated, Fig. 1 being a cross-section of the line with two trucks meeting at a turn-out, and Fig. 1^a a modification. Fig. 2 is a side-elevation of two trucks, one overriding the other one. Fig. 3 is an elevation and Fig. 4 is a plan of a loading-station, while Figs. 5 and 6, respectively, are similar views of a discharging station.

1 or 1^a is the carrying rail or rope (Figs. 1 and 1^a) and 2 are the standards supporting it, the rope or rail serving for taking up the whole traffic in both directions. The trucks consist of a curved frame 3 and two pairs of wheels 4 and 5, ramp rails 6 and 7 being linked to the ends of each frame 3 by aid of pins 8 and 9. In their unfolded state

the ramp rails bear on the carrying rope or rail 3, being supported thereon by rollers 10, 11. 12 is a cross beam fixed to the truck frame 3 and carrying two crabs 13, buckets 14 being suspended from these crabs by means of chains or cables, three (15, 16, 17) for each bucket. This mode of suspension acts to prevent the cross-beam from assuming an oblique position in case that the two buckets suspended from a truck are loaded unevenly. Whenever cross-beam 12 shows the tendency of leaning over to the side of the heavier weighted bucket, say to the right, the suspension cable 15 nearest to the carrying rail takes up the greater part of the load. In consequence, now, of the shorter arm of lever it is acting upon, as compared with the suspensions 16 and 17, it will prevent the beam from leaning over, the more so as at the same time the suspension cable 15 on the left hand side will now carry the full weight of the lighter bucket, this cable however acting upon a correspondingly longer arm of lever.

The cross-beams are provided at both ends with extensions 18 adapted to be folded upwards as shown in Fig. 1. They might however also be folded sideways or might be displaceable in a longitudinal direction. When they are unfolded, they may carry the crabs and in that case the breadth of the whole truck is determined by the full length of the cross-beam 12 and the extensions 18. The shifting over of the crabs to and from the extensions is effected automatically by guide rails disposed on the stations, said rails acting upon rollers 19 fixed on the crabs. In a similar manner the folding and unfolding of the extensions is effected by aid of guide rails acting upon rollers 20 fixed to the ends of the extensions. Cable clutches 21 are fixed to the cross beams 12 or to the car frames.

The stations of the ropeway are preferably arranged as shown in Figs. 3 to 6. Hinged switches 23, 24 acted upon by springs are provided for connecting the track rail or rope with a loop 22. Guide rails 25 and 26 disposed on the departure side of the station serve for shifting the crabs on the cross-beams and for folding and unfolding the extensions.

The operation of an aerial ropeway of the kind described is the following.

After loading the trucks are dispatched

with their extensions 18 folded and their ramp rails 6, 7 unfolded and on reaching the discharge station are released from the hauling cable. Before dispatching them anew after the buckets have discharged their contents, the ramp rails 6, 7 are folded up by suitable means and the trucks are then coupled with the hauling rope. On leaving the station guide rails 26 will unfold the extensions 18, guide rails 25 shifting the crabs 13 sideways upon the extensions.

If the truck on its return travel meets another truck coming from the loading station, it will override it as shown in Figs. 1 15 and 2, its buckets 14 passing aside of the buckets of the car below.

Although I have described my invention as applied to an overhead transporting device, I wish it to be understood that it is also 20 applicable with advantage to single rail transporting devices of a different type.

I claim:

1. In a transporting device in combination, a load carrying truck, means connected 25 with said truck for overriding another truck, a cross-beam on said truck, adapted to carry the load and means for varying the length of said beam.
2. In a transporting device in combination, 30 a load carrying truck, means connected with said truck for overriding another truck, a cross-beam on said truck adapted to carry the load, means for varying the length of said beam and buckets suspended from said 35 beam, each bucket being connected with three points of said beam.
3. In a transporting device in combination, 40 a load carrying truck, means connected with said truck for overriding another truck, a cross-beam on said truck adapted to carry

the load and extensions on said cross-beam.

4. In a transporting device in combination, a load carrying truck, means connected with said truck for overriding another truck, 45 a cross-beam on said truck adapted to carry the load and folding extensions on said cross-beam.

5. In a transporting device in combination, a load carrying truck, ramp rails 50 hinged to said truck and means for easily varying the breadth of said truck.

6. In a transporting device in combination, a load carrying truck, means connected with said truck for overriding another truck, 55 a cross-beam on said truck adapted to carry the load, extensions on said cross-beam and crabs displaceably disposed on said beam.

7. In a transporting device in combination, a load carrying truck, means connected 60 with said truck for overriding another truck, a cross-beam on said truck adapted to carry the load, extensions on said cross-beam, crabs displaceably disposed on said beam and buckets suspended from said crabs. 65

8. In a transporting device in combination, a load carrying truck, means connected with said truck for overriding another truck, a cross-beam on said truck adapted to carry the load, extensions on said cross-beam, 70 crabs displaceably disposed on said beam and buckets suspended from said crabs, each bucket being connected with three points of a crab.

In testimony whereof I affix my signature 75 in presence of two witnesses.

FRITZ WITTE.
